COLORIMETRIC APPARATUS

Roger S. Estey, Buffalo, N. Y., assignor to Spencer
Lens Company, Buffalo, N. Y., a corporation of
New York

Application September 14, 1940, Serial No. 356,775

3 Claims. (Cl. 88—14)

This invention relates to colorimetric apparatus and more particularly to a combined haemoglobinometer and micro-colorimeter.

An object of the invention is to provide a colorimetric instrument which requires only a small amount of the specimen for comparing the color of said specimen with a standard or with other colored substances.

Another object of the invention is to provide a device of the type set forth which will be simple and efficient in operation.

Another object of the invention is to provide an optical system in which a single structural element serves a plurality of functions thereby achieving economy and simplicity of structure.

Other objects and advantages of the invention will become apparent from the following specification taken in connection with the accompanying drawings. It will be understood that many changes in the details of construction and arrangement of parts may be made without departing from the spirit of the invention as expressed in the accompanying claims. I therefore do not wish to be limited to the exact details shown and described as the preferred form has been shown by way of illustration only.

Referring to the drawings:

Fig. 1 is a side view partially in section showing the construction of the instrument;

Fig. 2 is a front view also partially in section of the construction shown in Fig. 1;

Fig. 3 is a sectional view taken on line 3—3 of Fig. 1 looking in the direction of the arrows;

Fig. 4 is a sectional view on line 4—4 of Fig. 2 showing the cup operating mechanism; and

Fig. 5 is a fragmentary view showing the indicating device.

Referring more particularly to the drawings wherein similar reference characters designate corresponding parts throughout the several views, the device comprises a casing 1 having a base portion 2 containing the lamp 3. At the upper end of the casing 1 is the eyepiece 4 and biprism 5 which are in optical alignment with the plungers 6 and 7 and cups 8 and 9.

The base portion 2 is separated from the main casing 1 by the cover 11 having the openings 12 and 13 adapted to allow light from the lamp or light source 3 to pass therethrough and through said cups 8 and 9. Each of the openings 12 and 13 is in alignment with one of the cup members 8 and 9 respectively. Surrounding the lamp 3 in the base 2 is the light reflector and restrictor 14. The purpose of this member 14 is to reflect the light from the lamp 3 through the

openings 12 and 13 and to prevent loss of light due to the size of the casing.

The lamp 3 is secured in the socket 15 which socket has the extension 16 extending through a slot 17 in the side 18 of the base 2 of the casing and a threaded knob 19 is threaded onto the end of said extension member 16 which projects through said slot 17. The extension member 16 has a shoulder adapted to abut the member 18 surrounding the slot 17 and the knob 19 also has a similar shoulder adapted to abut the outer side of said member 18 surrounding said slot 17 so that by loosening the knob 19 on the threaded extension of the member 16, the lamp may be moved to adjusted position and then locked in said adjusted position by tightening the knob 19. The lamp is adapted to receive current through the wires 20 from the usual current supply.

The eyepiece 4 contains the ocular lens 10 which is adjustable in the usual manner to fit the requirements of the particular user of the instrument. The said eyepiece 4 also contains the usual field diaphragm 35 and eye point diaphragm 36.

The biprism 5 is adapted to be retained in position by the collar 21, which is secured in position by the screws 22.

The plungers 6 and 7 are formed of glass or a transparent plastic material such as Lucite, methyl-methacrylate, Catalin, or the like, and are secured at their upper ends to the holder 23 through the collars 24 which are secured to the member 23 and the member 23 is then secured to the casing 1 by the screws 25 or the like.

It will be noted that the cups 8 and 9 are secured into position with their upper ends converging and the plungers 6 and 7 are secured in fixed relation with the casing 1 at the same angle so that when the cups 8 and 9 are moved relative to said plungers 6 and 7 they will always be in aligned relation therewith.

The incident surface 31 of the biprism 5 is so positioned in cooperation with the emergent surfaces 38 and 39 that rays from the plungers 6 and 7 are rendered parallel and are bent forwardly along the axis of the eyepiece 4.

The dial 26 carries suitable designations and is adapted to cooperate with the indicator 27 on the casing 1 from which the result of the test may be read. To the dial 26 is attached the shaft 28 which projects through the bearing 40 and adjacent its inner end is secured the gear 29. The cup members 8 and 9 are socketed at their lower ends in the supports 30 and 31 respectively.

These supports 30 and 31 are threaded into

the arms 33 which in turn are attached to the rack members 32. The thread connection permits slight longitudinal adjustment of the position of the cups 8 and 9, thereby controlling the relationship between the positions of these cups and the indications on the dial 26.

When the dial 26 is turned, one of the cups is moved upwardly and the other downwardly, simultaneously, to the same extent. Therefore one of the cups 8 or 9 will move to enclose its respective plunger 6 or 7 to the same extent that the other of said cups 8 or 9 will move to expose its respective plunger 6 or 7, that is, while one plunger enters its cup the other plunger is simultaneously withdrawn from its cup to the same extent, and vice versa.

The light from the light source is reflected upwardly through the openings 12 and 13 by the reflector 14 and then passes through the cups 8 and 9 which are formed of a transparent material and then through the transparent plungers 6 and 7 into the biprism 5 and from there is directed into the eyepiece 4 where it is seen by the observer. The observer sees a circular field centrally divided into two portions which may or may not differ in color. If they differ in color the dial is turned and the relative positions of the cups changed until the two halves of the field appear the same in color and the dividing line substantially disappears.

In use of the instrument the unknown solution is placed in a particular one of the cups 8 or 9 and a known standard solution or other solution with which the unknown solution is to be compared is placed in the other of said cups 8 or 9. The dial 26 is then turned to change the relative positions of the cups 8 or 9 with respect to their respective plungers 6 or 7 until the two halves of the circular field seen in the eyepiece appear to be identical in color and the line separating these fields substantially disappears, and then the reading is taken on the dial 26.

The dial 26 carries two independent scales 42 and 43. One of these scales 42 expresses the ratio between the working depths of the fluids in the cups 8 and 9 for any position of the dial 26. This scale 42 may be expressed by the formula:

$$\theta = 360^\circ \times \frac{S}{S+1}$$

where θ is the angle from the zero mark of scale 42 on dial 26 to any scale mark having the numerical designation represented by S , and is adapted to record the concentration of coloring matter in one cup as related to the concentration of coloring matter in the other.

The second scale 43 on dial 26 is a measure of the working depth of the fluid in one cup without regard to the behavior of the other cup. This scale is expressed by the formula

$$\phi = 360^\circ - \frac{\text{constant}}{R}$$

where ϕ is the angle from the zero mark of scale 43 on dial 26 to any scale mark having the numerical designation represented by R , and serves to measure the color of substances by comparison with color standards of fixed thickness mounted in the cup support usually occupied by the cup not containing the sample being measured. For example this latter scale 43 may be used in connection with a suitably calibrated glass color standard to measure directly the haemoglobin content of a blood sample which has been con-

verted to acid hematin by well known chemical procedures.

It will be apparent that due to the construction the cups 8 and 9 may be made small enough to allow the testing of specimens of which only a small amount can be obtained such as blood, etc.

From the foregoing it will be seen that I have provided simple, efficient and economical means for obtaining all of the advantages, namely, for providing a new and improved construction of combined haemoglobinometer and colorimeter for use particularly where only small amounts of the specimen are obtainable.

Having described my invention, I claim:

15. In a device of the character described, a pair of cups and a pair of plungers, each of said plungers being aligned with and adapted to enter its respective cup, and said cups and plungers having their upper ends in converging relation, an eyepiece over said plungers, a single optical element between said plungers and eyepiece and in optical alignment therewith for converging the light beams from said plungers and directing said light into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
20. In a device of the character described, a pair of cups and a pair of plungers, each of said plungers being aligned with and adapted to enter its respective cup, and said cups and plungers having their upper ends in converging relation, an eyepiece over said plungers, a single optical element between said plungers and eyepiece and in optical alignment therewith for converging the light beams from said plungers and directing said light into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
25. In a device of the character described, a pair of cups and a pair of plungers, each of said plungers being aligned with and adapted to enter its respective cup, and said cups and plungers having their upper ends in converging relation, an eyepiece over said plungers, a single optical element between said plungers and eyepiece and in optical alignment therewith for converging the light beams from said plungers and directing said light into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
30. In a device of the character described, a pair of cups and a pair of plungers, each of said plungers being aligned with and adapted to enter its respective cup, and said cups and plungers having their upper ends in converging relation, an eyepiece over said plungers, a single optical element in which rays from both plungers enter a common face and emerge from two separate faces respectively into beams which are contiguous and parallel, between said plungers and eyepiece and in optical alignment therewith for directing light from said plungers into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
35. In a device of the character described, a pair of cups and a pair of plungers, each of said plungers being aligned with and adapted to enter its respective cup, and said cups and plungers having their upper ends in converging relation, an eyepiece over said plungers, a single optical element in which rays from both plungers enter a common face and emerge from two separate faces respectively into beams which are contiguous and parallel, between said plungers and eyepiece and in optical alignment therewith for directing light from said plungers into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
40. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
45. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
50. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a rack member for each pair of said cup and plunger members, a pinion in engagement with both of said rack members, and means for actuating said pinion to adjust said rack members for removing one of said plungers from its cup and moving the other of said plungers into its cup simultaneously and to the same extent.
55. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a pair of rack members on said upright and in the same converging relation as said plungers, a cup member on each of said rack members and adapted to be moved therewith, a pinion in engagement with both of said rack members, and means for actuating said pinion for simultaneously moving said rack members in opposite directions to cause one of said plungers to move into its respective cup and to cause the other of said plungers to move out of its respective cup simultaneously and to the same extent.
60. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a pair of rack members on said upright and in the same converging relation as said plungers, a cup member on each of said rack members and adapted to be moved therewith, a pinion in engagement with both of said rack members, and means for actuating said pinion for simultaneously moving said rack members in opposite directions to cause one of said plungers to move into its respective cup and to cause the other of said plungers to move out of its respective cup simultaneously and to the same extent.
65. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a pair of rack members on said upright and in the same converging relation as said plungers, a cup member on each of said rack members and adapted to be moved therewith, a pinion in engagement with both of said rack members, and means for actuating said pinion for simultaneously moving said rack members in opposite directions to cause one of said plungers to move into its respective cup and to cause the other of said plungers to move out of its respective cup simultaneously and to the same extent.
70. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a pair of rack members on said upright and in the same converging relation as said plungers, a cup member on each of said rack members and adapted to be moved therewith, a pinion in engagement with both of said rack members, and means for actuating said pinion for simultaneously moving said rack members in opposite directions to cause one of said plungers to move into its respective cup and to cause the other of said plungers to move out of its respective cup simultaneously and to the same extent.
75. In a device of the character described, a base, a source of illumination in said base, an upright on said base, a pair of plunger members having their upper ends in converging relation supported on said upright, an eyepiece, a single optical element in which rays from both plungers enter a common face and emerge from two separate faces respectively into beams which are contiguous and parallel between said plungers and eyepiece and in optical alignment therewith for directing light from said plungers into said eyepiece, a pair of rack members on said upright and in the same converging relation as said plungers, a cup member on each of said rack members and adapted to be moved therewith, a pinion in engagement with both of said rack members, and means for actuating said pinion for simultaneously moving said rack members in opposite directions to cause one of said plungers to move into its respective cup and to cause the other of said plungers to move out of its respective cup simultaneously and to the same extent.

ROGER S. ESTEY.
